MECHANICAL PENCIL

William Hume Brown, Santa Fe, N. Mex.

Application February 6, 1940, Serial No. 317,591

3 Claims. (Cl. 120—9)

The present invention relates to new and useful improvements in mechanical pencils and has for its primary object to provide, in a manner as hereinafter set forth, an instrument of this character embodying simple but novel means to facilitate rotating the point for projecting or retracting the lead.

Other objects of the invention are to provide an improved mechanical pencil point of the character described which will be comparatively simple in construction, compact, attractive in appearance and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

20 Figure 1 is an elevational view of a mechanical pencil embodying the present invention.

Figure 2 is an enlarged view of the point with the lead therein, the enlargement constituting the present invention being shown in vertical section.

25 Figure 3 is a view substantially similar to Fig. 2 but showing another form of the invention.

Referring now to the drawing in detail, it will be seen that the reference numeral 1 designates the usual barrel of a mechanical pencil which is provided with a pocket clip 2 and an eraser 3.

30 Rotatably mounted on the lower end of the barrel 1 is a tapered point 4 having a central aperture therein for the reception of the lead, as at 5. The tapered point 4 contains the usual mechanism for projecting and retracting the lead 5.

The point 4 includes a tapered tip 6 on its lower end, said tip being of suitable material, preferably metal. The tip 6 is also centrally apertured to receive the lead 5. At its lower end, the tip 6 terminates in an enlargement 7 of substantially the shape shown to advantage in Fig. 2 of the drawing.

35 In use, the enlargement 7 provides a convenient grip or knob to facilitate rotating the point 4 for projecting or retracting the lead 5. If desired, the enlargement 7 may be knurled or roughened in

order that a better grip may be had thereon. It will be observed that the shape of the enlargement 7 is such that it interferes in no way with writing when the pencil is held at different angles relative to the writing surface, as suggested in Fig. 1 of the drawing. The enlargement 7 also greatly facilitates inserting the pencil in the pocket as said enlargement readily opens said pocket in advance of the pencil without tearing, puncturing or otherwise damaging the fabric. The enlargement 7 also functions as a shield to prevent injury if the pencil is fallen on. Still further, the enlargement 7 strengthens or reinforces the point of the pencil.

In the modification illustrated in Fig. 3 of the drawing, the reference numeral 8 designates an enlargement which is adapted to be screwed or otherwise firmly secured in position on mechanical pencils which are manufactured as at present. Of course, the head 8 functions in a manner similar to the enlargement 7.

It is believed that the many advantages of an improved mechanical pencil point constructed in accordance with the present invention will be readily understood and although preferred embodiments of the device are as illustrated and described, it is to be understood that further modifications and changes in the details of construction may be resorted to which will fall within the scope of the invention as claimed.

What is claimed is:

1. A mechanical pencil comprising a barrel, a point rotatably mounted on the writing end of the barrel, said point being centrally apertured for the reception of a lead, a tapered tip fixed integral with the point, and an enlargement integral with the small end of the tapered tip.

2. A mechanical pencil comprising a tapered, rotary, centrally apertured tip for the reception of a lead, and an enlargement threadedly mounted on the small end portion of said tip.

3. A pencil comprising a tapered writing tip, a lead projecting centrally from said tip, and a knob on the small end portion of the tip for turning said tip and for spreading the walls of a pocket away from the lead when the pencil is inserted in said pocket.

WILLIAM HUME BROWN.
